(57) **CLAIM**

The ornamental design for a nose hair trimmer, as shown and described.

DESCRIPTION

FIG. 1 is a front, top perspective view of a nose hair trimmer, showing my new design;

FIG. 2 is a rear, bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is an exploded front, top perspective view of the nose hair trimmer; and,

FIG. 10 is an exploded rear, bottom perspective view thereof.

The broken lines in the figures illustrate portions of the nose hair trimmer that form no part of the claimed design.
